SEPARATOR FOR HEAT EXCHANGERS

Raymond C. McAllister, Painted Post, N. Y., assignor to Ingersoll-Rand Company, Jersey City, N. J., a corporation of New Jersey

Application November 8, 1934, Serial No. 752,005

6 Claims. (Cl. 257—29)

This invention relates to separators, and more particularly to a separator for heat exchangers, as for instance a compressor intercooler, through which compressed fluid flows from one cylinder to another.

One object of the invention is to effect the removal of entrained moisture from the pressure fluid.

Other objects will be in part obvious and in part pointed out hereinafter.

The drawing accompanying this specification and forming a part thereof is a section of the separator showing it applied to an intercooler.

Referring more particularly to the drawing, 20 designates, in general, a compressor system comprising low and high pressure cylinders 21 and 22 and a vertically disposed intercooler 23 through which compressed fluid flows from the former to the latter. The low pressure cylinder is accordingly connected to the casing 24 of the intercooler by a discharge conduit 25 which registers with an inlet opening 26 adjacent the upper end of the intercooler 23.

The intercooler 23 may be of a well known construction comprising a series of tubes 27 which extend longitudinally of the casing 24 and are supported at their upper and lower ends by tube sheets 28 and 29, respectively. The tube sheet 28 is seated upon the upper end of the casing 24 and supports a cover 30 the interior of which serves as a discharge chamber 31 for liquid issuing from the tubes 27. A conduit 32 connected to the cover 30 conveys the cooling liquid from the chamber 31 to a suitable destination.

Preferably, the tube plate 29 is of slightly smaller diameter than the interior of the casing 24, wherein it lies, to provide an annular passage 33 between these elements for the escape of condensate separated from the air as a result of its contact with the cool surfaces of the tubes 27. The tube plate 29 may be supported in any suitable manner and carries a head 34 having a chamber 35 through which cooling liquid passes to the tubes 27. A conduit 36 connected to the head 34 conveys cooling liquid to the chamber 35 from a source of supply (not shown).

In order that the fluid intended to be cooled may be brought repeatedly into intimate contact with a maximum cooling area of the tubes 27 the casing is provided with a series of baffles 37 which are arranged in staggered formation so that the fluid flowing through the casing is directed transversely of the tubes. Any suitable number of baffles may be provided for this purpose. Four 55 baffles are shown in the drawing, two being dis-

posed on one side of the casing and two on the opposite side. Thus, as the fluid flows through the casing it is caused to follow a serpentine path and, therefore, to traverse the tube nest repeatedly before issuing from an outlet opening or openings 38 located near the lower end of the casing 24, and preferably on the side opposite to that containing the inlet opening 26.

In accordance with the practice of the invention, means are provided for effecting the removal of moisture entrained in the compressed fluid prior to the entry of the fluid into the high pressure cylinder 22. The means selected for illustrative purposes comprising a casing 39 arranged about the lower portion of the casing 24 to which a plate 40, constituting a closure for the upper end of the casing 39, may be suitably secured to form a fluid tight joint at this point.

The plate 40 supports a tubular baffle 41 which encircles the casing 24 and extends with its lower end to a point below the outlet openings 38. Thus, as the compressed fluid issues from the outlet openings 38 it is first directed downwardly, thence curves upwardly around the lower edge of the baffle 41, flows upwardly through the annular space between the casing 39 and baffle 41 and continues through an intake conduit 42 connecting the high pressure cylinder with the upper portion of the casing 39, and above the outlet openings 38. The annular channel 43 defined by 30 the baffle 41 and the casing 24 and through which the compressed fluid flows from the inlet openings 38 into the casing 39 is preferably of somewhat restricted area in order to accelerate the velocity of the fluid entering the casing 39. 35

In the lower end of the casing 39 is a compartment 44 to receive the condensate extracted from the pressure fluid. The compartment 44 is defined by an intermediate wall 45 in the casing and an end head 46, the latter containing a 40 packing device 47 for effecting a seal about the conduit 36 which extends through the head 46. A valve 48 threaded to the head 46 provides a convenient means for periodically draining the condensate from the compartment 44. 45

In the wall 45 is a central opening 49 through which the conduit 36 extends and said opening also serves as a passage for conveying condensate from the upper portion of the casing 39 into the compartment 44. Preferably the lower portion of the casing 24 is in the form of a skirt 50 which extends to a point near the wall 45. The skirt conveys the condensate from the annular passage 33. It terminates below the baffle 41 and itself acts as a baffle to avoid intermingling 55

of the stream of pressure fluid flowing around the end of the baffle 41 and the condensate issuing from the annular passage 33.

- The operation of the device, briefly summarized, is as follows: Upon being discharged into the upper end of the intercooler the compressed air zig-zags downwardly around the baffles 37, thence flows through the outlet openings 38 into the passage 43 around the lower end of the baffle 41 and upwardly through the casing 39 to and through the conduit 42 into the high pressure cylinder 22. During the passage of the pressure fluid through the intercooler moisture is condensed through contact of the fluid medium with the tubes 27. The condensate thus formed precipitates to the bottom of the intercooler, whence it passes through the annular passage 33, the skirt portion 50 and the opening 49 into the compartment 44.
- 20 Any residue of condensed moisture entrained in the pressure fluid issuing from the outlet openings 38 will, of course, pass therewith through the annular restricted passage 43. Owing, however, to the highly accelerated velocity of the pressure fluid issuing from the annular passage 43, and to the further fact that at this point the direction of the air stream is sharply reversed, the moisture is cast out of the fluid stream into the lower or inactive portion of the casing, whence it passes through the opening 49 into the compartment 44.

I claim:

1. In a separator, the combination of a heat exchanger having inlet and outlet openings for pressure fluid, a casing to receive the discharge output of the heat exchanger, and means overlying the outlet opening for deflecting the fluid issuing therefrom to dynamically project moisture from the fluid stream into the casing.
2. In a separator, the combination of a heat exchanger having inlet and outlet openings for pressure fluid, a casing encircling the heat exchanger to receive its discharge output, and an annular baffle in the casing overlying the outlet opening for deflecting the fluid stream, thereby causing entrained moisture to be dynamically projected into an inactive portion of the casing.
3. In a separator, the combination of a heat exchanger having inlet and outlet openings for

pressure fluid, a casing encircling a portion of the heat exchanger to receive the fluid issuing from the outlet opening, and means in the casing for accelerating the velocity of the fluid issuing from the outlet opening and to deflect the fluid stream and thereby cause entrained condensate to be dynamically projected from the fluid stream into the casing.

4. In a separator, the combination of a heat exchanger having inlet and outlet openings for pressure fluid, a casing encircling a portion of the heat exchanger to receive the fluid issuing from the outlet opening, and an annular baffle in the casing for deflecting the fluid and cooperating with the heat exchanger to define a restricted passage for accelerating the velocity of the fluid and thereby cause entrained moisture to be cast from the fluid into an inactive portion of the casing.

5. In a separator, the combination of a vertical heat exchanger having inlet and outlet openings for pressure fluid, said heat exchanger having an outlet at its lower end for condensate, a casing encircling a portion of the heat exchanger to receive the pressure fluid and the condensate, a compartment within the casing for condensate, and an annular baffle encircling the heat exchanger and cooperating therewith to deflect the fluid and to define an annular restricted passage for accelerating the velocity of the fluid and thereby cause entrained moisture to be cast from the fluid into the casing.

6. In a separator, the combination of a vertical heat exchanger having inlet and outlet openings for pressure fluid, said heat exchanger having an outlet at its lower end for condensate, a casing encircling a portion of the heat exchanger to receive the pressure fluid and the condensate, a compartment within the casing for condensate, an annular baffle encircling the heat exchanger and cooperating therewith to deflect the fluid and to define an annular restricted passage for accelerating the velocity of the fluid and thereby cause entrained moisture to be cast from the fluid into the casing, and means for isolating the fluid stream from the condensate stream within the casing.

RAYMOND C. McALLISTER.
